UNITED STATES PATENT OFFICE

129,858

DESIGN FOR AN EMBLEM PIN

Alexander Stoller, New York, N. Y., assignor to Medical and Surgical Relief Committee of America

Application July 23, 1941, Serial No. 102,390

Term of patent 3½ years

To all whom it may concern:

Be it known that I, Alexander Stoller, a citizen of the United States, residing in the city, county, and State of New York, have invented a new, original, and ornamental Design for an Emblem Pin, of which the following is a specification, reference being had to the accompanying drawing, forming a part thereof.

Fig. 1 is a front elevational view of an emblem pin showing my new design,
Fig. 2 is a side view thereof,
Fig. 3 is a top view thereof.

I claim:

The ornamental design for an emblem pin, substantially as shown.
